(57) **CLAIM**

The ornamental design for a magnetic phone holder, as shown and described.

DESCRIPTION

FIG. 1 is a front, left and top perspective view of a magnetic phone holder, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a rear, right and bottom perspective view, shown in an alternate position.

The broken lines shown in the drawings illustrate portions of the magnetic phone holder that form no part of the claimed design.

1 Claim, 9 Drawing Sheets
